PROCESS FOR REFINING HYDROCARBON OILS
Warren C. Simpson, Berkeley, Calif., assignor to Shell Development Company, San Francisco, Calif., a corporation of Delaware

No Drawing. Application July 5, 1950,

Serial No. 172,193

9 Claims. (Cl. 196—14.12)

This invention relates to the art of treating hydrocarbon oils. It pertains more particularly to a process for removing undesirable substances such as coke-forming constituents and other related asphaltic substances from hydrocarbon oils, especially from residual petroleum hydrocarbon oils, to prepare the same for use as catalytic cracking stock and at the same time to produce asphaltic products.

The use of residual hydrocarbon oils either alone or mixed with, for example, oil distillates, as catalytic cracking stock is attractive for economical reasons because of the large production of residual oils in the refining of petroleum oils. Solvent deasphalting of topped crude oil and of vacuum flasher bottoms with propane, butane or with any other various deasphalting agents has been considered in this connection for the utilization of these residual oils in order to obtain catalytic cracking feed stock in excess of that now obtained by, for example, vacuum flashing of topped crude oil. In catalytic cracking stock, it is advantageous to reduce the amount of coke-forming constituents therein to a minimum for a number of reasons, chief of which is that the coke-burning capacity of the catalyst regenerator is frequently the limiting factor which determines the maximum allowable throughput of a catalytic cracking unit. It is well known that the constituents of petroleum oils which form coke most readily when subjected to catalytic cracking are the aromatic constituents and particularly the aromatic constituents which contain sulfur and nitrogen atoms.

It is a principal object, therefore, of this invention to provide a useful process for treating hydrocarbon oils, particularly residual hydrocarbon oils. A further object is to provide a process whereby coke-forming constituents are economically removed from petroleum oils. Another object is to provide a method for readily, economically and effectively removing coke-forming constituents and other related asphaltic substances from heavier hydrocarbon oils, such as residual hydrocarbon oils. A concomitant object is to produce an improved asphaltic composition. These objects will be more clearly understood and other objects will be evident from the detailed description of the invention.

Now, in accordance with the present invention, it has been found that the above and other objects are realized by a process wherein a hydrocarbon oil which contains undesirable impurities such as coke-forming constituents and/or other related asphaltic substances is treated with an amount of precipitating agent, preferably water-soluble, for said impurities, followed by separation of the resulting precipitated matter. This treatment may be and preferably is, combined with other concurrent and/or subsequent treatments to provide advantageous combination treatments or processes and wherein the above-described treatment is in the nature of a pretreatment.

Generally described, the present invention provides a process for treating a hydrocarbon oil, including shale oil and particularly residual petroleum oil, which contains undesirable coke-forming constituents and/or other related asphaltic constituents, which process comprises contacting said oil with a minor amount of one or more of a precipitating agent, preferably water-soluble, selected from the group of chemical compounds containing at least one of the variable-valence elements having an atomic number from 24 to 28, inclusive, namely, chromium, manganese, iron, cobalt and nickel, thereby precipitating said constituents as a complex therewith and separating the precipitated constituents from the oil. The sulfates and the halides of the above elements, particularly the chlorides of said elements, are especially effective precipitating agents for the coke-forming constituents of hydrocarbon oils. It is preferred to em-

2

ploy aqueous acidic (i. e., containing free acid, such as a mineral acid, viz. hydrochloric, nitric, phosphoric, sulfuric, etc.) solutions of the above compounds or the acidic salts of the above compounds as the precipitating agent.

With the application of the above treatment to asphalt containing residual petroleum hydrocarbon oil, the separated oil fraction after removal of the precipitated coke-forming constituents according to the invention may be advantageously further treated as by a deasphalting process employing propane, butane, or any other suitable deasphalting agent to produce a suitable catalytic cracking stock. In accordance with a preferred embodiment of the invention, the precipitation of the coke-forming impurities by employing the above-described agents is combined with the deasphalting process in a single operation with the attendant advantage that only one separation step is required since the precipitated coke-forming constituents separate out with the asphalt or propane insoluble phase.

In general, the inorganic compounds of the aforesaid metals, preferably the salts of the various inorganic mineral acids, are suitable, especially those salts and/or compounds wherein the metal represents the positive or cationic part of the salt. Suitable representative metal salts are the halides, such as ferric chloride, ferrous chloride, ferric bromide, nickel chloride, chromic chloride, cobalt chloride, manganese chloride; the acetates such as nickel acetate; the nitrates such as ferric nitrate, chromic nitrate, nickel nitrate and manganese nitrate; the sulfates such as ferrous sulfate, ferric sulfate, nickel sulfate, chromic sulfate, manganese sulfate and manganese sulfate, or mixtures of salts of the aforesaid elements; or aqueous solutions thereof. Steel mill pickel liquor, the average composition of which is approximately, in per cent by weight, 5% H_2SO_4 , 15% $FeSO_4$ and 80% H_2O is also useful as the precipitating agent. The principal coke-forming-constituent precipitating agent therein being ferrous sulfate.

The quantity by weight in which the precipitating agents of the invention are added to the hydrocarbon oil depends upon the quantity of the coke-forming constituents and other related asphaltic material therein. In general, a minor amount, usually an amount not more than 10% by weight of the oil to be thus treated, and in most cases not more than 5% and usually about 1%, by weight of the oil, effects sufficient precipitation of the coke-forming impurities and treatment of the oil.

The precipitation treatment of the coke-forming constituents and other related asphaltic substances is not confined to any particular temperature or temperature range. The precipitation treatment is suitably carried out at normal or elevated temperatures. When applying normal or slightly elevated temperatures the precipitated, coke-forming constituents may not settle out readily, particularly if the treated hydrocarbon oil is a heavy viscous residual oil. This difficulty may, however, be overcome by increasing the temperature or by the addition of diluents or solvents to thin out the viscous oil or by centrifugation or by any other suitable method. When, however, the precipitation of the coke-forming constituents of a hydrocarbon oil, such as a residual oil, is carried out immediately prior to or concurrently with a deasphalting step, such as by propane deasphalting, this difficulty is ordinarily not present since, due to fluidity of such a hydrocarbon mixture, the precipitated coke-forming constituents along with the precipitated asphalt readily separate out.

After the removal of the precipitated coke-forming constituents together with the precipitating agent therefor, said agent may be recovered therefrom if desired, by suitable chemical and/or solvent or separation treatment. For example, if ferric chloride is employed as the precipitating agent, the iron salt may be removed and recovered from the precipitate by heating the precipitate with water and an oil solvent, such as benzene, to hydrolyze the iron salt and to precipitate hydrous ferric oxide. It is preferred however to treat the separated precipitated matter with water at relatively low temperature, usually about 20°C., to leach out and dissolve the precipitating agent therein. This is advantageous since it permits the recovery of the precipitating agent, e. g.

ferric chloride, unchanged. If however, the precipitation of coke-forming constituents in a petroleum residual oil is accompanied by or subsequently followed by a deasphalting operation, it may be preferable to separate the precipitated coke-forming constituents and asphalt together since the precipitating agent, particularly ferric chloride, functions as a blowing oxidation catalyst, in the preparation of air-blown asphalts, thereby obviating the necessity of adding a blowing catalyst to the recovered asphalt. It appears that the incorporation of the ferric chloride or other agent in the asphalt simultaneously with the separation (deasphalting) of the asphalt from the other oil constituents results in a more uniform incorporation of the agent in the asphalt and hence a more effective air-blown operation.

The following examples representing the practice of the present invention as applied to the treatment of exemplary materials illustrate the invention and set forth the advantages to be obtained by practicing the invention, but they are not to be construed as limitative thereof.

EXAMPLE I

An isopentane solution of the isopentane soluble portion of a distillation residue of a Santa Maria crude was shaken with a minor amount of a saturated aqueous solution of ferric chloride at room temperature with the result that heavy, easily removed insoluble complexes precipitated out. Examination of these complexes showed that the hydrocarbon portion thereof contained high percentages of sulfur and of nitrogen, greater than the percentages of sulfur and of nitrogen of the hydrocarbons remaining dissolved in the isopentane solution. It was also found that the amount of complex formed could be controlled up to a certain limit by the amount of saturated aqueous ferric chloride solution added. Another experiment was performed using steel mill pickle liquor containing ferrous sulfate as the precipitating material and similar results were also obtained.

EXAMPLE II

To demonstrate that a ferric chloride treatment precipitates coke-forming constituents such as nitrogen and sulfur-containing constituents of an aromatic character, from residual hydrocarbon oils, a topped Wilmington crude (long residue) was propane deasphalting after being subjected to a ferric chloride treatment in accordance with the invention. The topped crude was heated to about 212° F. and about 1% by weight, of said crude, of anhydrous ferric chloride was added thereto with stirring and the mixture was held at 212° F. for about 10 minutes after which it was cooled to about 150° F. in a propane deasphalting apparatus, wherein it was intimately contacted with propane in a volume ratio of propane to topped crude of 4 to 1, at a temperature of about 150° F. Mixing and settling times of 30 minutes and one hour, respectively, were used, the precipitated material and asphalt being separated from the propane solution of oil. For purposes of comparison another sample of the same topped Wilmington crude was propane deasphalting under the same conditions but without any ferric chloride treatment. The properties of the products as a result of the above treatments are given in Table I below:

Table I

Penetration Index		-1.3	+0.9

*1% FeCl₃ based on topped crude, 10 minutes at 212° F.

Although the data presented in Table I indicate that the ferric chloride treatment caused a very slight drop in the yield of deasphalting oil, the reproducibility of the oil yield values is probably not much better than the indicated difference. The analyses of the oils obtained show that in the case of the ferric chloride treatment an oil of high A. P. I. gravity is produced and that this oil has a Conradson carbon residue of only about 2/3 that of the oil produced by propane deasphalting alone. The Conradson carbon residue is an indication of the coke forming tendencies of oil when used as catalytic cracking stock. Also the sulfur and nitrogen contents of the ferric chloride treated oil are lower than for the untreated oil. The extent of lowering of the sulfur and nitrogen contents of ferric chloride treated oil can be controlled by varying the amount of ferric chloride used.

The ferric chloride treatment produced an oil with a lower refractive index and a lower specific dispersion which indicate a lower aromatic hydrocarbon content therein. The bromine number of the ferric chloride treated oil is also lower, indicating a reduced amount of unsaturated hydrocarbon material therein. It is also pointed out that the iron content of the treated and untreated oils is low in both cases and amounts to only a few thousandths of a per cent, thus clearly showing that the added ferric chloride and the complexes it forms with the coke-forming impurities are thrown into the asphalt or propane insoluble phase in the deasphalting operation.

The properties of the asphalts obtained are also given in Table I. The data demonstrate that ferric chloride treatment yields asphalt of lower penetration index than is obtained by propane deasphalting alone. The asphalt was particularly suitable as a blowing flux.

In view of its higher A. P. I. gravity, lower Conradson carbon residue, lower sulfur and nitrogen content, lower aromatic content and lower bromine number, the ferric chloride treated and propane deasphalting oil is a better and more desirable catalytic cracking stock than oil obtained by propane deasphalting alone. This was demonstrated by comparative tests wherein these oils were subjected to catalytic cracking. The operating conditions of the catalytic cracking and the distribution of the products obtained are set forth in Table II below:

Table II

CATALYTIC CRACKING OF OILS FROM A WILMINGTON LONG RESIDUE—INFLUENCE OF FERRIC CHLORIDE ON PROpane DEASPHALTING OPERATION

Temperature, 500° C.
Process period, 10 minutes.
Two cycles.
Catalyst Surface Area about 75 m.²/g.

	Vacuum Flashed Distillate (55% of long residue)	Propane De- asphalting Oil (71.5% of long residue)	Propane- FeCl ₃ -De- asphalting Oil (69% of long residue)
W. Percent Reacted	50.0	49.4	50.8
W. Percent Gasoline (C ₅ -200° C. B. P.)	28.4	26.7	28.0
W. Percent Coke	8.8	9.3	7.8
W. Percent Gas (C ₄ and lighter)	12.8	13.4	15.0
W. Percent Gas oil (over 200° C. B. P.)	50.0	50.6	49.2

Catalytic cracking data for a vacuum flashed distillate from the same topped crude which is a normal feed stock for the catalytic cracking operation are also given for purposes of comparison. The suitability of the various oils tested as catalytic cracking feedstock can be determined by comparing the product distribution of each since they have all been cracked to 50% conversion. The data of Table II clearly demonstrate that the oil obtained by ferric chloride treatment and propane deasphalting is superior as a catalytic cracking stock to the oil obtained by propane deasphalting alone, since the ferric chloride treated oil produced more gasoline, more gas (including C₄) and substantially less coke. In fact, the ferric chloride treated oil produced less coke on a percentage basis than did the vacuum flashed distillate which represents only 55% of the long residue. Thus, the ability of ferric chloride to remove coke-forming constituents from catalytic cracking stocks is thereby demonstrated.

5
EXAMPLE III

To demonstrate that ferric chloride treatment may also be used to produce suitable catalytic cracking feed stock from short residues (vacuum flasher bottoms) the following experiments were performed.

Vacuum flasher bottoms were heated to about 212° F. and 1% by weight of said bottoms of anhydrous ferric chloride was added with agitation. The mixture was then heated to about 390° F. and held at this temperature for a period of about 30 minutes with frequent agitation. It is considered that the reactions between ferric chloride and the various coke-forming constituents and related asphaltic material of the flasher bottoms are hastened with an increase in temperature. Thereupon the ferric chloride treated flasher bottoms were cooled to about 100° F. and deasphalted with 10 volumes of propane per volume of flasher bottoms. A single stage batch extraction was carried out in a horizontal rotary mixer with a mixing time of about 30 minutes and a settling time of about one hour. The above-indicated mixing and settling time are not critical however, and may be greatly varied depending upon operating conditions, equipment, ferric chloride concentration, etc. Another portion of the same vacuum flasher bottoms (pitch) was propane deasphalted under similar conditions but without the ferric chloride treatment. The yield data and the properties of the oil produced by these methods from the flasher bottoms are presented in Table III together with an analysis and properties of the vacuum flasher bottoms for the purpose of comparison.

Table III

USE OF FERRIC CHLORIDE IN DEASPHALTING PROCESS
PRODUCTION OF CATALYTIC CRACKING STOCK FROM
A WILMINGTON FLASHER PITCH (SHORT RESIDUE)

[Volume ratio, propane/Pitch=10/1. Temperature, 100° F.]

Specific Dispersion.....	do	143	136
Bromine Number.....		19.3	17.4
Percent Fe.....			0.000(4)

These experiments demonstrated (as the data presented in Table III show) that a ferric chloride treatment is especially useful in the preparation of catalytic cracking feed stock from residual oils. While the amount of oil recovered was only very slightly reduced by the ferric chloride treatment, the oil obtained by ferric chloride treatment had a higher A. P. I. gravity value and a considerably lower Conradson carbon residue indicating thereby that at least a portion of the coke-forming constituents had been removed. The ferric chloride treated oil also had lower sulfuric and nitrogen contents as well as a lower molecular weight. In addition the refractive index and the specific dispersion of the ferric chloride treated oil was lower, indicating a reduced aromatic content and therefore less refractory composition as compared with the oil prepared by propane deasphalting alone. A lower content of unsaturated material in the ferric chloride treated oil is indicated by the lower bromine number. Furthermore, the iron content of the ferric chloride treated oil is extremely low, indicating that the ferric chloride and the coke-forming constituents and related asphaltic materials with which it forms complexes are thrown into the asphalt or propane insoluble phase during the propane deasphalting step.

In view of the above results and observations it is considered that ferric chloride treated and propane deasphalted residual oil give a superior catalytic cracking feed stock over a similar oil obtained by propane deasphalting alone. Accordingly in order to demonstrate the above, these oils were subjected to catalytic cracking.

6

A vacuum flashed distillate of similar stock was also subjected to catalytic cracking for the purpose of comparison. The operating conditions of the catalytic cracking and the distribution of the products obtained are set forth in Table IV below:

of the untreated and treated oil showed a reduction in sulfur and nitrogen content of the treated oil (i. e. that portion which did not form a complex). Listed below in Table VI are various inorganic metal salts according to the invention which formed complexes; also is listed that portion of the oil with which complexes were formed.

Table VI

	Percent weight oil which formed complexes
Nickel chloride	3.52
Nickel sulfate	9.0
Nickel acetate	2.88
Manganese chloride	10.4
Manganese sulfate	7.6
Chromic chloride	17.0
Chromic sulfate	approx. 10
Cobalt nitrate	8.4

A feature of the subject invention relates to the production of air blown asphalts. It is known that oxidation catalysts, for example, ferric chloride, act as catalysts in the air blowing of asphalt. Actual tests have shown that ferric chloride added to a residual oil before or during a deasphalting operation, for example, a propane or butane, etc., deasphalting process in accordance with the invention is as effective a catalyst as when added during blowing flux formulation. Thus, it is possible to make double use of the coke-forming constituents precipitating agents. For example, ferric chloride treatment may not only be employed as a method of producing more suitable catalytic cracking stocks from residual oils but also to produce asphalts therefrom which blow to desired penetration and softening point more rapidly than ordinary blowing fluxes.

I claim as my invention:

1. A method of producing a suitable catalytic cracking feed stock from an asphaltic residual petroleum oil which also contains constituents which promote coke-formation in catalytic cracking operation which process comprises contacting said oil simultaneously with a saturated hydrocarbon of from 3 to 5 carbon atoms as deasphalting agent and with a minor amount of from about 1% to about 10% by weight of the oil of a water-soluble

inorganic salt containing as cationic portion at least one of the variable-valence elements having an atomic number of from 24 to 28, inclusive, as essentially the only chemically reactive precipitating agent for said coke-forming constituents, whereby a phase comprising a solution of oil in said deasphalting agent and a phase comprising the resulting precipitate and asphalt are formed, and separating the resulting precipitate and asphalt from the solution of oil in the deasphalting agent.

- 5 2. A method according to claim 1, wherein the hydrocarbon deasphalting agent is essentially propane.
3. A method according to claim 2, wherein the inorganic salt is a halide.
4. A method according to claim 2, wherein the inorganic salt is a chloride.
- 15 5. A method according to claim 2, wherein the inorganic salt is ferric chloride.
6. A method according to claim 1, wherein the inorganic salt is ferrous sulfate provided as steel mill pickle liquor.
- 20 7. A method according to claim 1, wherein the inorganic salt is chromic chloride.
8. A method according to claim 1, wherein the inorganic salt is manganese chloride.
- 25 9. A method according to claim 1, wherein the inorganic salt is nickel sulfate.
